(57) **CLAIM**

The ornamental design for an air cleaner housing, as shown and described.

DESCRIPTION

FIG. 1 is a perspective view of an air cleaner housing according to our new design shown in the environment of an engine;

FIG. 2 is a top plan view thereof;

FIG. 3 is a perspective view of an air cleaner housing according to our new design;

FIG. 4 is a right side elevation view thereof;

FIG. 5 is a bottom plan view thereof;

FIG. 6 is a front plan view thereof;

FIG. 7 is a rear plan view thereof;

FIG. 8 is a left side elevation view thereof; and,

FIG. 9 is a top plan view thereof.

The broken lines shown herein are for illustrative purposes only and form no part of the claimed design.
